(57) **CLAIM**

The ornamental design for a holder for rigging attachment for use on a fishing rod or pole, as shown and described.

DESCRIPTION

FIG. 1 is a top, front, left end isometric view of a holder attachment embodying my invention;

FIG. 2 is a top, rear and left end isometric view of the holder attachment illustrated in FIG. 1;

FIG. 3 is a top view of the holder attachment;

FIG. 4 is a front view thereof;

FIG. 5 is a rear view thereof;

FIG. 6 is a left end view thereof;

FIG. 7 is a right end view thereof; and,

FIG. 8 is a bottom view thereof.
